PEDESTAL FOR RAILWAY CARS

Filed Oct. 5, 1928

UNITED STATES PATENT OFFICE

JOHN D. THOMPSON, OF UNION CITY, NEW JERSEY, ASSIGNOR TO AMERICAN CAR AND FOUNDRY COMPANY, OF NEW YORK, N. Y., A CORPORATION OF NEW JERSEY

PEDESTAL FOR RAILWAY CARS

Application filed October 5, 1928. Serial No. 310,560.

This invention relates to railway cars and more particularly to journal box pedestals therefor, and it is an object of this invention to provide an improved pedestal which shall be of simple and rugged construction, readily manufactured and easily applied and which will provide an adequate support for the car body and a suitable guide for the journal box.

It is also an object of this invention to provide a pedestal of the type described which may be cast integral or built of a number of separately formed parts.

Other objects and advantages of this invention will be apparent from the following description taken in conjunction with the accompanying drawings in which:

Figure 1 is a broken view of a car equipped with journal box pedestals constructed in accordance with this invention;

Fig. 2 is a partial transverse vertical section of the car shown in Fig. 1 taken at one of the journal boxes, the wheel and axle being shown in elevation;

Fig. 3 is a vertical longitudinal section taken on the line 3—3 of Fig. 2 and showing the pedestal in elevation;

Fig. 4 is a top plan view of the pedestal of Figs. 1 to 3, the members forming the car sill being shown in broken lines;

Fig. 5 is a side elevation of a pedestal of modified construction;

Fig. 6 is a section taken on the line 6—6 of Fig. 5; and

Fig. 7 is a top plan view of the pedestal shown in Figs. 5 and 6.

In the drawings, the invention is shown in connection with a car having a body 1 of any suitable or desired construction comprising sills 2 composed of spaced Z-bars 3 having their webs vertical and their upper flanges 4 projecting outwardly and joined by a cover or floor plate 6. The lower flanges 8 of the members 3 project inwardly, but the members 3 are spaced apart so that the flanges 8 do not meet. Projecting between the members 3 of the sills 2 are pairs of pedestals 10 which are of greater width than the opening between flanges 8 and are received in openings

12 formed by cutting away portions of the flanges 8.

As shown in Figs. 1 to 4, inclusive, a pedestal 10 comprises a web 14 of substantially inverted U-shape having the parallel side portions 16 joined at their upper ends by the connecting portion 18. The lower ends of the side portions 16 are provided with oppositely disposed laterally projecting attaching flanges 20, while intermediate their ends the side portions 16 are connected by oppositely disposed outwardly projecting attaching flanges 22. The attaching flanges 20 and 22 are joined at each side portion 16 by the parallel outwardly projecting flanges 24 which extend along the edges of the side portions 16 of the web 14 between the flanges 20 and 22, while the attaching flanges 22 are braced and connected to the web 14 by the inwardly projecting ribs 26 and the outwardly projecting ribs 28. The pedestal is further reinforced by a continuous rib 30 which projects outwardly from the center of the web 14 and extends from end to end thereof, being of uniform projection along the portion 18 of the web and of gradually increasing projection from each end of the side portions 16 to the region of the attaching flanges 22.

In the modified construction shown in Figs. 5, 6, 7, the pedestal is formed with the web 14 of inverted U-shape having the side portions 16 and connecting portion 18 and provided with the flanges 20, 22 and 24 and ribs 26 and 28 as in Figs. 1 to 4, but in this construction the attaching flanges 22 are also joined by the parallel flanges 29 which extend along the edges of the connecting portion 18 and side portions 16 above the flanges 22.

In use, the pedestals are placed with their upper portions projecting through the openings 12 into the space between the members 3, the flanges 22 engaging beneath the flanges 8 of the members 3 and being secured thereto by bolts 32. A journal box 34, in which is journaled an axle 36 having wheels 38 thereon, is inserted between the side portions 16 of each pedestal and guided thereby and the pedestals are supported from the journal boxes 34 by springs 40 mounted in the spring seat 42 of the journal box 34 and engaging

a boss or spring guide 44 formed integral with the web 14. After the journal boxes 34 are in position in the pedestals, the flanges 20 of the pedestals of each side of the car are connected by a tie bar 46 secured to the flanges 20 by bolts 48.

While the pedestal has been shown and described as an integral cast member, it is to be understood that it may be formed of a plurality of separately formed parts secured together and that the invention is not limited to the exact details shown and described as it is obvious that various modifications thereof within the scope of the claims will occur to persons skilled in the art.

What is claimed is:

1. In a car, a sill comprising spaced members having inwardly projecting flanges, and a pedestal projecting between the members 20 of said sill and having oppositely disposed outwardly projecting flanges secured to the flanges of said sill members.

2. A pedestal comprising an inverted U-shape web and laterally projecting attaching flanges lying in a common plane and connecting opposite portions of said web.

3. A pedestal comprising an inverted U-shape web and oppositely disposed outwardly projecting flanges lying in a common plane and connecting the side portions of said web.

4. A pedestal comprising a U-shape web, an outwardly projecting reinforcing flange extending substantially from end to end of 35 said web and oppositely disposed outwardly projecting attaching flanges connecting the side portions of said web.

5. A pedestal comprising a web having parallel side portions and a connecting portion joining ends of the parallel portions, spaced parallel outwardly projecting flanges extending along the parallel portions of the web and oppositely disposed outwardly projecting attaching flanges connecting the 45 parallel portions of the web.

6. A pedestal comprising a web having parallel portions and a connecting portion joining ends of the parallel portions and oppositely disposed outwardly projecting attaching flanges connecting the parallel portions of said web intermediate the ends thereof.

7. A pedestal comprising a U-shape web having outwardly projecting end portions 55 forming attaching flanges, outwardly projecting oppositely disposed attaching flanges connecting oppositely disposed portions of said web, reinforcing flanges connecting said attaching flanges and reinforcing ribs connecting said oppositely disposed attaching flanges and web.

8. A pedestal comprising a web having spaced parallel portions bent outwardly to form attaching flanges at one end and joined 65 by a connecting portion at the other end, out-

wardly projecting oppositely disposed attaching flanges connecting the parallel portions of the web intermediate the ends thereof and reinforcing flanges projecting from the edges of the parallel portions of said web and connecting the attaching flanges.

9. A pedestal comprising a web having parallel side portions and a portion connecting said side portions and attaching flanges spaced from said connecting portion of said web and connecting said side portions of said web.

10. A pedestal comprising a web having parallel side portions and a portion connecting said side portions and attaching flanges connecting said side portions and lying in a plane parallel to the plane of said connecting portion of said web.

11. A pedestal comprising a web having spaced side portions and spaced attaching flanges connecting said side portions.

12. A pedestal comprising a web having spaced side portions and parallel attaching flanges connecting said side portions, said attaching flanges lying in a common plane.

In witness whereof I have hereunto set my hand.

JOHN D. THOMPSON.
